United States Patent Office.

CHARLES F. PIKE, OF PROVIDENCE, RHODE ISLAND, ASSIGNOR TO HENRY C. MAHURIN AND CHARLES SMEAD, OF BOSTON, MASSACHUSETTS.

Letters Patent No. 99,471, dated February 1, 1870.

IMPROVED RAILWAY CATTLE-CAR.

The Schedule referred to in these Letters Patent and making part of the same.

To all whom it may concern:

Be it known that I, CHARLES F. PIKE, of the city of Providence, county of Providence, State of Rhode Island, have invented a new and useful Improvement in Railway Stock-Cars; and the following is a correct description thereof, reference being had to the accompanying drawings, making a part of this specification, in which—

Figure 1 is an interior side elevation of a car, with my improvements, showing the car closed;

Figure 2, an exterior elevation of the same, with side closed;

Figure 3, a plan view of the car; and

Figure 4, a cross-section.

My invention has for its object, the transportation of stock over railways with increased comfort.

It consists in constructing the walls of stock-cars with open slats, over which an outer part of similar construction is made to slide, in such a manner that the car may be closed up, or opened, to allow a free circulation of air, as desired, according to what the weather may require for the comfort of the stock. The doors of the car are made to slide in the outer part.

Also, in partitions constructed of wire net-work, so as to allow a free circulation of air, and furnished with pintles, upon which they turn, and which can be inserted in holes in iron bars at the top and bottom of the car, thus enabling the partitions to be adjusted at any distance apart, according to the size of the animals.

O represents the slats, of which the walls of the car are constructed, with openings, O', between them.

N represents the slats of the outer part. This outer part is held to the wall by the strips N' N", forming grooves, in which the outer part slides such a distance that the slats N may be made to coincide with the inner slats O, or cover the open spaces O', as desired, either to ventilate the car; or, in case of cold or stormy weather, to close it.

Either side or end of the car may be opened or closed

by itself, according to the direction of the wind, without effecting the other parts of the car.

The doors K slide in grooves, N' N", which are attached to the outer sliding portion the car.

F are the partitions formed of wire net-work, as shown.

The posts f are formed with pintles, G H, at their upper and lower extremities, which pintles turn in holes, W, formed in the iron bars E E', which bars are placed in the upper part of the car, and in the floor D.

The partition can thus be turned back like a gate, to give room for the animal to take its proper place, after which it is swung into the position shown in fig. 1, and is fastened by the bolt I, which enters a hole, W', in the bar E'. A row of holes is formed in each of the bars E, E', and E", as shown, the purpose of which will presently appear.

The pintle H is made long enough to permit the partition or gate F to be raised up and removed, thus allowing the car to be used for ordinary freight. By the same means the gates are adjusted to any of the above-mentioned holes in the iron bars, according to the distances apart they are required to be, to accommodate stock of different sizes.

What I claim as new, and desire to secure by Letters Patent, is—

1. The outer sliding wall of a stock-car, constructed as shown and described; in combination with the sliding doors K, as and for the purpose hereinbefore set forth.

2. The adjustable partitions F, constructed of wire net-work, and furnished with pintles G and H, and bolts I, in combination with the iron bars E, E', and E", as and for the purpose shown and described.

CHARLES F. PIKE.
